UNITED STATES PATENT OFFICE.

WASYL HUCAL, OF CHICAGO, ILLINOIS.

INTERMITTENT MECHANISM.

1,387,054.

Specification of Letters Patent. Patented Aug. 9, 1921.

Application filed June 17, 1919. Serial No. 304,819.

To all whom it may concern:

Be it known that I, WASYL HUCAL, a citizen of the United States, residing at Chicago, in the county of Cook and State of Illinois, have invented certain new and useful Improvements in Intermittent Mechanism, of which the following is a specification.

The invention has for an object to provide 10 an intermittent mechanism suitable for use with moving picture apparatus, either for projecting or in photography, which will be positive in action, silent in operation and involve a comparatively small amount of 15 power for its operation. It is an important aim of the invention to present such a mechanism which will have a minimum number of parts and be liable in a minimum degree to loss of efficiency through wear. It is 20 also an aim to give such a mechanism which may be produced in a very compact form. Another aim is to provide a mechanism of this character which may be readily used upon machines such as are now generally 25 employed.

Additional objects, advantages and features of invention will appear from the construction, arrangement, and combination of parts involved in the invention, one embodiment 30 of which is described herein and shown in the drawings, wherein,

Figure 1 is an elevational view of the mechanism in its casing, with part of the casing broken away.

Fig. 2 is a top view thereof.

Fig. 3 is a cross sectional view on the line 35 3-3 of Fig. 1.

Fig. 4 is an edge view of the disk 11.

Fig. 5 is a similar view of a modification 40 of the disk.

There is illustrated a case 10 of circular form, within which a cam disk 11 is revolvably mounted, being carried upon a shaft 12 journaled in the back wall 13 and cover plate 45 14 of the case. The back wall 13 forms a part of the main body of the case, which includes a cylindrical wall portion 15 integral with the wall 13, and carried upon this body portion there is a mounting arm 50 16 having a dove tail channel 17 thereacross, adapted to receive slidably therein a correspondingly formed stud rail or other element as may be provided for the mounting of the intermittent mechanism. Other means may

of course be employed for mounting the case 55 if desired.

The disk 11 is secured upon the shaft 12 and is provided with a cam groove or channel 18 in its periphery, rectangular in cross section, and for its major part having opposite sides in planes at right angles to the axis of the shaft 12, the body of the disk projecting on each side of the groove in the form of flanges 19, as illustrated in Fig. 3. A shaft 20 is mounted in the casing to lie 60 medially within this groove, being located upon a horizontal axis in the lower part of the case in the present instance, the body of the casing being open at the lower side and having extensions 21-22 upon which 65 there is secured an intermittent retainer cap 23, the bearing for the shaft 20 being formed in the opposed faces of the cap and extensions 21-22. Fixed upon the shaft 20 in a plane at right angles thereto and coincident with the axis of the shaft 12, there is a driven cam block 24 rectangular in section 70 at right angles to its shaft and of a size to fit snugly in the groove 18. Its outer faces are slightly curved convexly from one side 75 to the other. At one side of the disk, the groove is given a spiral form, as though it had been twisted a quarter turn, so that the angular junction between the bottom and side of the groove at one side becomes 80 slightly inclined inwardly toward the axis of the cam disk, and also toward the opposite side of the groove, in the form of a spiral having a radius equal to the radius of the corners of the block 24 with respect to 85 its axis, and having an axis concentric with the shaft 12 on a radius equal to the distance between the axis of the shaft 12 and the axis of the shaft 20. At the same time, the bottom face and one side face of the 90 groove assume a form corresponding to that of an archimedean screw having a curved axis, instead of a rectilinear axis. This involves the deflection of the side of the groove outwardly into the flange 19 for a distance, 95 the continuation of the surface of one side of the flange in one direction forming the bottom of the groove at the far end of the spiral. If desired, the spiral part of the groove may have the form of a one-eighth 100 turn, instead of one-quarter turn, indicated in Fig. 4, and a larger intermittent sprocket 105 employed to insure the same degree of move-

ment as would be obtained by the first form described.

The disk 11 is formed with a semi-spherical recess 25 at one side from which projects 5 a hub 26, the back of the case receiving the outer part of the hub snugly for bearing. On the back wall 13 of the case there is formed a cylindrical wall 27 projecting into the recess 25 and in close spaced relation to 10 the hub 26. The wall 27 stops short of the bottom of the recess 25. The back wall 13 and plate 14 each lies in close spaced relation to the adjacent face of the disk.

The shaft 20 for the intermittent drive 15 does not require to be very strong for the amount of power to be transmitted, but on account of the abrupt action of the cam on the member 24 a severe side thrust is involved, and therefore a very heavy part 28 20 is formed on the shaft 20 fitted in suitable bearing portions in the cap 23.

The shaft 20 is either connected to the shaft of the intermittent sprocket in the moving picture mechanism, or the intermittent 25 sprocket mounted directly upon the shaft 20 in the moving picture mechanism.

It will be seen that the device gives the 30 advantage of a very large bearing area upon the driven cam whereby the rotative movement imparted thereto may be quickly checked without excessive wear upon the engaging surfaces or liability of fracture, and the character of the device is such as to readily enable its operation in oil, the casing 35 10 being filled with oil ordinarily.

The wall 15 may be cylindrical through-

out, and the cap plate 23 formed with a slight medial enlargement 28 in which the block 24 may rotate.

The parts all have a good oil-tight fit, 40 and the construction permits the case to be supplied with sufficient oil to partly or completely fill it, reducing wear, sound and vibration.

What is claimed:

A device of the character described comprising a circular case having a back body portion and integral cylindrical wall, an oil-tight cover plate thereon, a shaft concentrically revoluble in the case, a cam 50 thereon having a peripheral groove with partly spiral form in parts, a second member engaged in the groove for intermittent rotation thereby under rotation of the cam, said second member being revoluble on an 55 axis at right angles to that of the cam, and having a shaft extended in each direction on its axis, and enlarged at its inner parts, said case having an opening in the wall, for lateral movement of the second member into 60 and out of engagement with the cam, a cap member to close the opening having bearing parts to engage the enlarged parts of the last named shaft, the case and cap having parts to form an oil-tight closure around the 65 shaft.

In testimony whereof I have affixed my signature in presence of two witnesses.

WASYL HUCAL.
